VEHICLE WINDSHIELD WIPER BLADE ASSEMBLY

Raymond A. Deibel, West Falls, N.Y., assignor to
Trico Products Corporation, Buffalo, N.Y.

Filed Aug. 8, 1973, Ser. No. 386,522

Term of patent 14 years

Int. Cl. D12—16

U.S. Cl. D12—155

FIG. 1 is a top plan view of a vehicle windshield wiper blade assembly showing my new design.

FIG. 2 is a sectional view thereof taken along the line II—II of FIG. 1.

FIG. 3 is a perspective view thereof.

The side opposite to that shown in FIG. 3 is a mirror image thereof.

I claim:

The ornamental design for a vehicle windshield wiper blade assembly, as shown and described.
